ADJUSTABLE SASH SPRING

Jesse G. Hesseltine, Sedgwick, Colo.

Application November 22, 1948, Serial No. 61,467

6 Claims. (Cl. 292—76)

1

This invention relates to an adjustable sash holder, designed to replace the conventional sash weights and spring balances and has for its primary object to provide a durable and inexpensive device for frictionally retaining the sash in adjusted raised positions.

Another object of this invention is to provide a sash retaining device, which will eliminate rattling of the sash in the frame and which is adjustable for use with various types of sashes, regardless of the weight thereof.

Another object of this invention is to provide means for frictionally retaining a window sash in adjusted raised positions in a window frame, the means including a resilient strip adapted to bear against the edge face of the frame and hold the same in an adjusted raised position, means being provided for adjusting and controlling the pressure of the device against the frame.

These and ancillary objects and other structural features of merit are attained by this invention, a preferred embodiment of which is set forth in the following description and illustrated in the accompanying drawings, wherein:

Figure 1 is a side elevational view of a sash retaining device or holder, constructed in accordance with the principles of this invention, and showing the same in operative association with a fragmentary portion of a window frame and sash;

Figure 2 is a vertical sectional view of the sash holder, illustrating in section a fragmentary portion of the supporting frame;

Figure 3 is a view in perspective of a fragmentary portion of a window sash, illustrating the recess formed therein for accommodating the present invention;

Figure 4 is a front elevation view of the instant invention, and

Figure 5 is a transverse sectional view taken on line 5—5 of Figure 2.

Referring now particularly to the drawings, the numeral 10 designates a conventional window sash, which is slidably disposed and mounted in a conventional frame 12, fragmentary portions of the conventional structure being shown by way of environment for the instant invention, generally designated by the character reference 14.

In carrying out the instant invention, a recess 16 is formed transversely in the edge face 17 of the sash, adjacent the edge face of the frame. A resilient elongated strip 18 is anchored at one end, by a screw or similar fastening member 20 to the edge face of the sash, the fastening member being disposed in the edge face. The strip 18 is bent outwardly and downwardly as at 24, to

define an enlarged end 26, which is offset from the longitudinal plane of the anchored end. A cylindrical casing 28 is laterally carried by the terminating portion of the end 26 and is disposed in the recess 16. An opening 30 is formed in the end 26 in alignment with the central portion of the casing 28, for a purpose to be later described. A similar opening 32 is formed in the outer end of the casing and an externally threaded lug 34 is disposed through the opening 32 and longitudinally disposed in the casing. A disk-shaped head 36 is formed on the lug and is adapted to bear against the inner wall 38 of the recess. A compression spring 40 is disposed in the casing, about the lug 34 and bears against the end 26, to urge the offset end 26 and the casing outwardly from the recess and the edge face 17 of the sash.

Means is provided for adjusting the tension on the spring 40, to vary the outward pressure on the offset end 26, bearing against the edge face of the frame, in accordance with the weight and type of sash and the amount of clearance between the sash and the frame. In the latter respect, a disk 42 is disposed on the externally threaded lug, for longitudinal adjustment thereon, the spring 40 bearing against the disk 42 and the offset end 26. A longitudinally disposed slot 44 is formed in the upper portion of the casing to receive an offset section or lug or tongue 46 on the disk. A transverse adjusting slot or kerf is formed in the outer end of the lug 34 to accommodate a blade or screw driver, which is inserted through the opening 30. Thus, rotation of the lug 34 correspondingly moves the disk 42 longitudinally thereon, the latter being guided by means of the tongue 46 disposed in the slot 44 and movement of the disk adjusts the tension spring.

Thus, it is to be apparent that there has been provided a novel and useful device, which can be secured to a standard window sash, with a minimum of alteration, the only alteration to the frame being the provision of the recess 16. The sash holder will function in a dependable manner to securely retain the sash in the desired raised position and the frictional pressure thereof can be easily overcome by manual pressure applied to the sash to raise or lower the same.

However, since many other purposes and various embodiments of this invention will become apparent to those skilled in the art, it is to be understood that certain changes may be carried out, as coming within the scope of the appended claims.

Having described the invention, what is claimed as new is:

1. The combination with a window casing and sash slidably mounted therein, the sash being provided with a recess on the edge face adjacent the edge face of the frame; of means for frictionally holding the sash in adjusted raised positions, said means including a resilient strip anchored at one end to the sash and having an offset end, a cylindrical casing laterally extending from said offset end and disposed in said recess; resilient means housed in said casing for urging said casing and offset end outwardly therefrom to bear against the edge face of the frame, and means for adjusting the tension on said resilient means.

2. An adjustable sash holder for frictionally retaining a sash, having a recess formed in its edge face, in adjusted positions in a window frame including a resilient strip anchored at one end to the edge face of the sash, a cylindrical casing laterally carried by the other end of the strip, and disposed in said recess, an externally threaded lug disposed in said casing and having a disc end bearing against the inner wall of the recess, a spring disposed in said casing for urging the casing and end of the strip outwardly from the recess, a disc adjustably disposed on the lug and bearing against the spring, means for moving said disc longitudinally in the casing on the lug to adjust the tension on the spring.

3. The combination of claim 2, wherein said last means includes a slot in said casing, a tongue,

on said disc slidably disposed in said slot, and means for rotating said lug to move the disc.

4. An adjustable retaining means for a window sash slidably mounted in a frame including a resilient strip anchored at one end to the edge face of the sash, an offset end on said strip, a cylindrical casing laterally carried by said offset end and disposed in a transverse recess formed in the edge face of the sash, a lug bearing against the rear wall of the recess and extending into said casing, a spring in said casing and concentrically disposed about said lug, a disc adjustably mounted on said lug and bearing against the inner end of the spring, means for adjusting said disc to adjust the tension on said spring.

5. The combination of claim 4, wherein said disc is threaded on the lug and has an offset section slidably engaged in said casing.

6. The combination of claim 4, wherein said last means includes an offset section on said disc, a longitudinally extending slot in said casing for slidably receiving said offset section and means for rotating said lug.
